SPRAY NOZZLE

This application is related to my copending application Ser. No. 650,794, filed July 3, 1967 and the application of Casper Goff, Ser. No. 775,310.

FIELD OF THE INVENTION

This invention relates to a nozzle and, more particularly, to a type thereof for mixing a stream of pressurized viscous liquid material with pressurized air to produce a relatively fine spray of the liquid material.

BACKGROUND OF THE INVENTION

This invention arose out of a need for a nozzle which would effectively apply a viscous liquid material, such as cold asphalt, onto a surface, such as a roof, in a uniform, fine spray having a wide angle of discharge. The process, of which this spraying operation is a part, is explained in detail in my copending application Ser. No. 650,794, filed July 3, 1967.

Nozzles which were commercially available on the market were not completely satisfactory due to the fact that they were incapable of satisfactorily dispersing the viscous materials, and they plugged up too quickly. Furthermore, the commercially available spray nozzles are not capable of discharging large volumes of viscous material in the desired spray pattern. Some nozzles permitted the flow of a large volume of viscous material, but the viscous material was not effectively broken up into small droplets as the material discharged from the nozzle. Thus, they have not been effective in laying a thin layer of cold asphalt material onto a roof.

Accordingly, it is a primary object of this invention to provide a nozzle which is capable of handling large volumes of viscous material, and which is capable of discharging the material in a wide uniform spray of small droplets so that the viscous material is effectively dispersed in a thin even layer on a surface.

It is a further object of this invention to provide a nozzle, as aforesaid, which is simple to manufacture through the utilization of readily available parts, which is easy to disassemble for cleaning purposes and which will not plug up so that cleaning and maintenance thereof is minimized.

Other objects and purposes of this invention will be apparent to persons acquainted with apparatus of this general type upon reading the following specification and inspecting the accompanying drawings, in which:

FIG. 1 is a schematic illustration of the circuit for supplying pressurized viscous liquid and pressurized air to a nozzle of the type embodying the invention;

FIG. 2 is a top view of the nozzle taken along the line II-II of FIG. 1;

FIG. 3 is a sectional view taken along the line III-III of FIG. 2;

FIG. 4 is a sectional view taken along the line IV-IV of FIG. 3.

Certain terminology will be used in the following description for convenience in reference only and will not be limiting. The words "right" and "left" will designate directions in the drawing to which reference is made. The words "in" and "out" will refer to directions toward and away from, respectively, the geometric center of the device and designated parts thereof. Said terminology will include the words thereof specifically mentioned, derivatives thereof and words of similar import.

SUMMARY OF THE INVENTION

The objects and purposes of the invention have been met by providing a nozzle having an elongated hollow body with first and second inlet openings connected to an outlet opening. An elongated tubular member extends coaxially through the outlet opening and into the first inlet opening, and the viscous material moves from the second inlet opening through the tubular member. The exterior surface of the tubular member and the wall defining the outlet opening are spaced between

their ends to provide a cylindrical passageway through which flows the pressurized air from the second inlet opening. A least one radial opening is provided in the tubular member adjacent the outlet end thereof to interconnect the tubular member with said passageway, whereby to permit the flow of pressurized air into the stream of viscous liquid just before it is discharged.

DETAILED DESCRIPTION

The system 10 (FIG. 1) for supplying pressurized viscous liquid material to the nozzle 11 will be briefly described primarily to provide a disclosure of one type of environment in which the nozzle is capable of use. The system 10 comprises a pumping device 12 which moves viscous liquid material, such as cold asphalt, from a source 17 through a conduit 13 to a control device 14 and thence to the nozzle 11. The pumping device 12 is driven hydraulically by a power device 16 which supplies hydraulic fluid through the conduit 26 thereto causing the internal mechanism of the pumping device to draw the highly viscous material from the tank 17 and deliver same under pressure to the conduit 13. A valve device 18 is connected to the conduit 26 by conduit 27 and to the reservoir 3 by the conduit 29, whereby hydraulic fluid can be caused to bypass the pumping device 12.

Pressurized air is generated in the compressor device 19 and is supplied through a conduit 21 to a variable chamber apparatus 22 which has a piston 23 slideably disposed therein and a rod 24 connecting the piston 23 to the valve device 18. A conduit 25 interconnects the variable chamber apparatus 22 with the control device 14 which controls the volume of pressurized air being delivered to the nozzle 11. The conduit 21 and 25 communicate with the variable chamber apparatus 22 on the same side of the piston 23, whereby a sudden increase in air pressure will cause the valve device 18 to bypass the hydraulic fluid.

The nozzle 11 (FIGS. 2-4) comprises a hollow body 3 having a cylindrical recess 32 in one end thereof, the walls thereof being threaded at 33. A pair of cylindrical openings 36 and 37 are provided in the opposite end of the body 31. The opening 36 communicates with one side of the recess 32 adjacent the inner end thereof. A threaded passageway 38 connects the opening 36 with the recess 32. The passageway 38 is coaxial with the recess 32 and of lesser diameter.

A pair of conduits 41 and 42 are threaded connected with threads in the walls defining the openings 36 and 37, respectively, and they connect the control device 14 to the nozzle 11. In this particular embodiment, the conduit 41 is connected through the control device 14 to the conduit 13 and the conduit 42 is connected to the conduit 25. The conduits 41 and 42 are preferably stiff and of substantial length so as to space the control device from the nozzle 11. Thus, the operator directs the nozzle by holding the control device in his hand, and he will be spaced a considerable distance from the nozzle 11 so that the material can be discharged conveniently from the nozzle near the roof surface and will not splatter onto the operator. The conduits 41 and 42 are in the range of 3 to 6 feet long.

A tubular member 43 has an external thread 44 adjacent one end which is threaded engaged with the threads in the passageway 38 so that the interior 46 of the tubular member 43 communicates with the opening 36 and conduit 41. It is recognized, of course, that the passageway 38 could be machined to a predetermined dimension and not have threads thereon so that one end of the tubular member could be held therein by a press fit. A plurality of openings 47 are provided in the wall of the tubular member 43 adjacent the front end thereof. A beveled end surface 48 is provided on the front end of the tubular member 43.

The nozzle 11 further comprises a hollow, cylindrical end member 51 having threads 52 on the external surface thereof adjacent one end which is threaded engageable with the threads 33 in the recess 32. The internal wall 53 of the hollow

d member 51 is of a greater diameter than the external diameter of the tubular member 43 so as to define an annular passageway 54 therebetween which communicates with the recess 32, opening 37 and conduit 42. The wall 50 defining the front end of the passageway 54 adjacent the front end of the member 51 is beveled at 56 and in fluidtight engagement with the beveled surface 48 on the tubular member 43 so as to prevent the flow of air between the end of the tubular member and the beveled surface 56. A discharge aperture 57 is provided in the front end wall of the end member 51, and the combined air and liquid are urged through the aperture 57, which may be varied in size and/or shape to accommodate variations in viscosity or discharge pattern.

OPERATION

The operation of the device embodying the invention will be apparent from the foregoing description, but will be summarized hereinbelow for convenience.

It is contemplated that the operator will hold the control device 14 in his hand for controlling the volume of pressurized viscous asphalt material and pressurized air being delivered to the nozzle 11. The control device 14 is rendered operable by a control button indicated schematically at B. Assuming that the operator has operated the button B to permit the flow of pressurized asphalt liquid and pressurized air to the nozzle 11 through the conduits 41 and 42, respectively, the asphalt liquid will flow into the opening 36, thence through the interior 46 of the hollow member 43 and be discharged through the aperture 57 in the end member 51. Pressurized air will pass through the opening 37, recess 32, annular passageway 54 and thence through the openings 47 into the stream of the viscous asphalt liquid flowing through the tubular member 43. The pressurized air is at a greater pressure than the pressure on the asphalt liquid so that no asphalt will be backed up into the annular passageway 54. The air entering the tubular member 43 will effectively break the viscous asphalt liquid into small droplets so that as the liquid asphalt and air are discharged through the aperture 57 in a diverging stream of small droplets liquid asphalt which will be uniformly deposited upon surfaces at which the aperture 57 is directed.

Since the tubular member 43 provides a straight-through connection between the opening 36 and the aperture 57, a large volume of liquid asphalt is permitted to pass therethrough without clogging the nozzle. Furthermore, the introduction of pressurized air into the stream of asphalt liquid adjacent the nozzle 57 creates an effective turbulence at the aperture 57 to effectively break up any particles which tend to cling to the internal surfaces surrounding the aperture 57. Still further, since the beveled face 48 is disposed in fluidtight engagement with the beveled face 56 of the front wall 50, the air will not flow directly from passageway 54 to aperture 57 but must flow radially inwardly through the openings 47 so as to become effectively entrained with the liquid asphalt. As the openings 47 are disposed adjacent the discharge aperture, the air causes the discharged asphalt to thus be rapidly separated into a diverging stream of small droplets.

The nozzle 11 is comprised of only three simple pieces which can be quickly disassembled for cleaning, if desired, and the outer surface of the front end of member 51 can be wired to facilitate such disassembly.

Although a particular preferred embodiment of the invention has been disclosed above for illustrative purposes, it will be understood that variations or modifications of such disclosure which lie within the scope of the appended claims, are fully contemplated.

claim:

1. A nozzle for mixing a stream of pressurized gas with a stream of pressurized liquid and discharging the mixture, comprising:

a rigid body means having a first passageway extending therethrough, the rear end of said first passageway being connectable to a source of liquid under pressure, said first

passageway having inlet and outlet portions disposed at angles to each other, the front part of said outlet portion being defined by tubular means;

wall means defining passage means in said body means spaced radially from said first passageway near the front end thereof, said passage means being annular and concentrically encircling said tubular means;

means defining at least one opening communicating between said first passageway and said passage means adjacent said front end of said first passageway;

wall means defining a second passageway in said body means communicating at one end of said passage means and connectable at its other end to a source of pressurized gas, said second passageway being substantially parallel with and spaced from the inlet portion of said first passageway;

said body means including a main body part containing the inlet portion of said first passageway, the rear part of the outlet portion of said first passageway, the second passageway and a recess defining the rear end of said passage means, said rear part of said outlet portion of said first passageway being of lesser diameter than the diameter of the adjacent end of said recess;

a cylindrical part firmly and partially received into said recess and having a coaxial opening defining the outer limits of the front end of said passage means;

said tubular means being in liquidtight engagement at its front end with said cylindrical part and at its rear end with the walls defining said rear part of said outlet portion of said first passageway; and

whereby the gas moves through the second passageway and through said passage means and through said opening and mixes with the liquid contained in said first passageway, the liquid-air mixture being discharged through the front end of said first passageway.

2. A nozzle according to claim 1, wherein said cylindrical part and said tubular means are threadedly connected to and readily separable from said main part.

3. A nozzle structure for mixing a stream of pressurized fluid, particularly gas, with a stream of pressurized liquid and for discharging the resulting mixture, comprising:

rigid body means having a first passageway extending therethrough, said first passageway having inlet and discharge openings adjacent the opposite ends thereof, said inlet opening being connectable to a source of a first pressurized fluid;

wall means defining a second passageway in said body means spaced radially from said first passageway near the front end thereof;

wall means defining a third passageway in said body means and communicating at one end thereof with said second passageway and connectable at its other end to a source of a second pressurized fluid;

said third passageway being connected to said second passageway substantially adjacent one end of said second passageway, the other end of said second passageway being closed; and

means defining a small opening means for providing the sole communication between said first and second passageways, said opening means being disposed closely adjacent said discharge opening and being spaced slightly rearwardly therefrom for providing communication between the forward portion of said first passageway and the forward end of said second passageway, whereby all of the second pressurized fluid supplied to said second passageway must flow through said opening means so as to mix with the first pressurized fluid in said first passageway prior to discharge of said mixture through said discharge opening, the mixture of said fluids taking place directly adjacent said discharge opening for creating an effective turbulence at the discharge opening so as to effectively separate the liquid into individual particles.

4. A nozzle structure according to claim 3, wherein said body means includes a first tubular portion having an opening therein defining the outlet portion of said first passageway, said body means further including a second tubular portion disposed in surrounding relationship to said first tubular portion and radially spaced therefrom so as to define an annular space disposed in concentric encircling relationship to said first tubular portion, said annular space constituting said second passageway, the forward ends of said first and second tubular portions being disposed in fluidtight sealing engagement with one another for closing the forward end of said second passageway, and said opening means including at least one small opening extending radially through the wall of said first tubular portion closely adjacent the forward end thereof for permitting the second fluid to flow from said second passageway into said first passageway.

5. A nozzle structure according to claim 3, wherein said body means includes a main body part having an inlet portion of said first passageway formed therein;

said main body part further having a tubular portion fixedly secured thereto with the open interior of said tubular portion defining the outlet portion of said first passageway; said body means further including a removable end member fixedly secured to the forward end of said main body part, said end member being disposed in surrounding relationship to the forward end of said tubular portion, said tubular portion and said end member having opposed walls spaced from one another so as to define said second

5 passageway therebetween, said third passageway being formed in said main body part and being in communication with said second passageway;

10 said end member and said tubular portion each having wall thereon adjacent the forward ends thereof with said wall being disposed in fluidtight sealing engagement with or another for effectively closing the forward end of said second passageway, said opening means including at least one small opening extending radially through the wall of said tubular portion directly adjacent the discharge end thereof for providing communication from said second passageway directly into said first passageway substantially adjacent the discharge end thereof.

15 6. A nozzle structure according to claim 5, wherein said end member comprises a hollow cylindrical part disposed in surrounding relationship to the forwardmost end of said tubular portion, said cylindrical part having the rearward end thereof fixedly connected to said main body part, the other end of said cylindrical part having cylindrical wall means disposed in surrounding relationship to and closely adjacent the forward end of said tubular portion, said cylindrical wall means having said discharge opening formed therein, and said cylindrical wall means and the forward end of said tubular portion each having annular surfaces disposed in fluidtight sealing engagement with one another when the cylindrical part is fixedly secure to the main body part.
